CLAIM

I claim the ornamental design for a dinosaur sweatshirt hood, as shown and described.

DESCRIPTION

FIG. 1 is a front perspective view of a dinosaur sweatshirt hood;

FIG. 2 is a front view of the dinosaur sweatshirt hood of FIG. 1;

FIG. 3 is a rear view of the dinosaur sweatshirt hood of FIG. 1;

FIG. 4 is a top view of the dinosaur sweatshirt hood of FIG. 1;

FIG. 5 is a right side view of the dinosaur sweatshirt hood of FIG. 1;

FIG. 6 is a left side view of the dinosaur sweatshirt hood of FIG. 1;

FIG. 7 is a front view of the dinosaur sweatshirt hood of FIG. 1 in a laid-flat position with a zipper in an open position; and,

FIG. 8 is a front view of the dinosaur sweatshirt hood of FIG. 1 with a zipper in an open position.

The zipper follows the curvature of the dinosaur sweatshirt hood. The facial features are an applied motif that follows the curvature of the dinosaur sweatshirt hood.

The dash-dot-dash broken line defines the bounds of the claim and forms no part of the claimed design. The even-length broken lines along the hood portion of the dinosaur sweatshirt hood depict features that form no part of the claimed design. The even-length broken lines beyond the boundary line depicts portions of the dinosaur sweatshirt hood that form no part of the claimed design.
